FLOW RESTRICTOR

John O. Hruby, Jr., Burbank, Calif., assignor to Rain Jet Corp., Los Angeles, Calif., a corporation

Application May 31, 1955, Serial No. 512,129

7 Claims. (Cl. 299—60)

This invention relates to restrictors for controlling the flow of fluids through conduits.

While the invention may be employed advantageously for various conduit installations, including, for example, heating systems and overhead sprinkler systems, I have chosen to illustrate and describe the invention as the same may be embodied in a lawn sprinkler system, for when so described, the advantages of the invention become readily apparent.

In conventional lawn sprinkler systems, a pipe leading from a water line is laid in the ground and a plurality of short risers are connected to it for attaching sprinkler heads to the pipe. In some installations several sprinkler heads are connected to a single pipe in a series arrangement, and in other installations several pipes are employed, each of which may include a plurality of sprinklers in series arrangement. In the case of several sprinklers arranged in series, an upstream sprinkler will receive water at a higher pressure than a sprinkler located downstream thereof, and thus the spray of water from the upstream sprinkler will be greater than that from a downstream sprinkler. Also, where different lengths of pipe are employed to connect sprinklers at different distances from a common water line, the water pressure in a sprinkler farthest away from the water line will be less than that in a sprinkler positioned nearer the water line. Then, too, the water pressure in a sprinkler positioned at a given level will be greater than the pressure of water in a sprinkler of the same system but positioned at a higher level.

For at least partially equalizing the pressure of several sprinklers in a given installation, one may employ pipes of different diameters, i. e. a sprinkler proximate the main water line may be connected into the system with a riser of small diameter, while a sprinkler further removed from the water line is connected by a riser of larger diameter. As the various sizes of standard pipes are limited, this method of equalizing pressures in a single system is not entirely satisfactory and is relatively expensive to install, for it requires the use of pipe fittings of various sizes and an expert knowledge of water pressures and how pressures may be controlled by utilizing pipes of given diameters. Furthermore, accurate adjustment is not attainable from the use of pipes of standard sizes.

An object of this invention is to provide an improved method and means for equalizing flow of fluid from a plurality of outlets in a system.

The sprinkler systems of the type herein illustrated are designed for installation on a "do-it-yourself" basis, i. e. installation may be made simply and reliably even by home owners who are not skilled in the pipe fitting art, and accordingly it is an object of this invention to provide a means for equalizing the pressure water from spaced apart sprinkler heads in a sprinkler system which is simple to install and adjust for uniform distribution of water, no matter what the pipe arrangement of the sprinkler system may be.

2

A further object of the invention is to provide an improved restrictor for a pipe which is simple in construction and may be manufactured on a mass production basis for the purpose of supplying the public with restrictors at low cost.

Further objects and advantages of the invention will appear in the following part of this specification, wherein the details of construction and mode of operation of a preferred embodiment of the invention are described with reference to the accompanying drawing, in which:

Fig. 1 is a representation of a portion of a pipe in a lawn sprinkler system, the pipe having a plurality of risers connected thereto for mounting sprinkler heads;

Fig. 2 is a side elevation of a riser and a portion of the water pipe to which it is connected, and a sprinkler head mounted thereon, the riser and pipe being shown partially in central vertical section to expose a flow restrictor embodying the invention;

Fig. 3 is a central vertical section through the restrictor; and

Fig. 4 is a perspective view of the restrictor, before being mounted in a system.

Referring to the drawing in greater detail, and with the use of reference numerals, a water conduit or pipe for supplying water to several sprinklers in a lawn sprinkler system is shown and designated generally by reference numeral 10. The pipe 10 is made up of a plurality of pipe sections 11 which are threadably connected end to end with pipe T's 12. One end 13 of the pipe 10, herein referred to as the upstream end, is adapted to be connected to a valve controlled water line (not shown) by which water is admitted to the pipe. The other end of the pipe 10 terminates in an elbow 14 by which the sprinkler furthest removed from the water line is connected to the pipe. The elbow 14 is herein referred to as the downstream end of the pipe 10. The pipe sections are of uniform size. The horizontal flow passage in the pipe T 12 appearing in Fig. 2 is designated by numeral 15, while the vertically extending passage thereof is designated by numeral 16.

Each of the upwardly extending legs of the elbow 14 and the upwardly extending leg of each pipe T threadably receive a pipe nipple or riser. These risers are designated by numerals 18, 19, 20 and 21, respectively, the riser 21 being fitted into the elbow 14. In the illustrated embodiment the risers are of equal length so that the pipe 10 may be laid at a uniform depth in the lawn. The vertical passage through the riser 18 is designated by numeral 22.

To complete the installation of a lawn sprinkler system, sprinkler heads of any desired type are connected to the top end of each riser. The drawing shows a sprinkler head 24 connected to the top end of riser 18, which head is of the general type illustrated and described in my Patent No. 2,639,191, issued May 19, 1953.

As thus far described, it will be apparent that the pressure of water in the upstream riser 18 will be greater than that in any of the risers located downstream thereof, and should water under pressure be admitted to the pipe 10 before sprinkler heads are mounted on the several risers, it will be seen that the stream of water from the riser 18 will be higher than that from the remaining risers which in turn produce streams of less height as the downstream end 14 of the pipe 10 is approached. Such decrease in water pressure will result in a smaller area of water distribution from the most downstream sprinkler than from any sprinklers located upstream thereof.

This invention makes it possible to simply and effectively equalize the pressure or flow of water from each of the several risers in a sprinkler system. This is accomplished by positioning a restrictor, embodying the invention, in each riser and then adjusting the opening of each

restrictor as required to obtain the same volume flow from each sprinkler head.

The restrictor illustrated in the drawing is designated generally by reference numeral 26, and it comprises a tube 27 and a collar 28 around the tube. The collar 28 is preferably formed as a right-circular cylinder having an annular upper end face 29, a lower annular end face 30, and side walls 31. Screw threads are formed in the side walls 31 for threadably fitting the restrictor in the lower end of a riser, the risers being internally screw-threaded in their lower ends for this purpose. The collar has an axially extending bore 32 formed therein for receiving the tube 27.

The tube 27 is formed of malleable material, preferably of brass which is resistant to corrosion. It has an axially extending passage 34. For simplicity in the manufacture of the restrictor, the tube may be cut from long length of tube having an outside diameter approximating that of the diameter of the bore 32 to permit easy fitting of the tube in the collar. The tube is of greater axial length than the collar and is flared outwardly in the upper end thereof to form an annular flange 35 which keeps the tube from sliding downwardly in the bore of the collar. At its lower end, the tube is pinched together, thereby widening it at opposed sides 36 thereof, and preventing axial movement of the tube upwardly in the collar. Pinching or flattening of the tube results in forming the passage 34 thereof as an elongate opening 37 in the lower end of the tube.

Before positioning the restrictor in a riser, the flattened sides of the lower end of the tube are made to be closely adjacent each other so that the opening 37 will be narrower than when finally adjusted to proper size. The restrictor is threadably fitted into the lower end of a riser with the pinched end thereof directed toward the supply pipe 10, and preferably the internal threads in the risers and the axial length of the collar and tube of the restrictor are so dimensioned that the lower end of the tube will not extend into the passage 15 of the pipe, this for the purpose of eliminating turbulence in the pipe. In the illustrated embodiment the flattened end of the tube extends to the plane of the inside wall defining the passage 15.

With a restrictor 26 positioned as shown in each riser of the sprinkler system, the size of the restrictor openings may be easily adjusted to equalize the rate of flow of water from the several risers. This is accomplished before attaching the sprinkler heads, by inserting a suitable tool, e. g. screw driver, downwardly in a riser and into the flattened end of the tube 27, thereby to widen the opening 37 in that tube to a size which will result in the desired rate of flow. Such adjustment of the size of the opening 37 is made for each riser until the streams of water from respective risers are equal in height. The opening 37 in a restrictor located downstream of another restrictor will ordinarily be adjusted to greater size than that in a restrictor upstream thereof. Of course, should it be desired that a given sprinkler distribute water over an area larger than that for other sprinklers in the same system, the restrictor opening 37 for the given sprinkler may be adjusted to greater size for accomplishing such purpose. It is to be noted, too, that should a given restrictor opening inadvertently be made larger than desired, it is but a simple operation to remove the riser containing it, and to pinch the side walls of the tube closer together thereby to decrease the area of its opening 37.

When the streams of water from the several risers are of the desired relative heights, the water is then turned off in the water line, and sprinkler heads are secured on the risers to complete the installation. Upon operation of the thus completed system, it will be found that the lawn area of water distribution from each sprinkler will be proportioned to the height of the stream of water from its respective riser observed prior to installing the sprinkler heads. It follows, too, that a lawn sprinkler

system containing a plurality of uniformly spaced apart sprinkler heads of a common size, and adjusted to produce streams of water of equal height from the risers thereof according to the method described above, will distribute water evenly over the lawn.

Not only do the restrictors of this invention serve to permit easy adjustment of flow of water to respective sprinkler heads, but, also, they function as filters in keeping sand and other foreign particles carried by the water from passing up into the sprinkler heads, and this filtering action is especially pronounced when the restrictors are arranged in the risers in the manner shown in the drawing with the pinched end of the tube 27 directed downwardly in the riser toward the supply pipe 10. When the restrictors are arranged in this way, sand carried by the water in pipe 10 will collect in a pocket 39 around the tube 27, such pocket being defined by the lower end face of collar 28, the outside surface of the downwardly projecting portion of the tube 27, and the inside surface 20 of the riser 18.

From the above, it is seen that the invention provides a reliable restrictor of simple construction which may be readily and easily adjusted to secure desired flow of fluid from each outlet in a conduit system.

It is to be understood that the form of my invention herein shown and described, is a practical and preferred example of the same, and that changes may be resorted to within the scope of my invention, which is not limited to the details disclosed herein, but is to be accorded the 30 full scope of the claims so as to embrace any and all equivalent structures.

Having described my invention, what I claim as new and desire to secure by Letters Patent is:

1. A flow restrictor for a tubular conduit, comprising a tube of malleable material having a passage extending therethrough, said tube being of lesser outside diameter than the inside diameter of said conduit, means fixed around the tube for mounting the tube in the conduit and for preventing flow of fluid through the conduit other than through said passage, one end of the tube being pinched to define an opening which is smaller in area than the cross section of said passage, said one end being free of said means whereby said opening may be made larger in area by inserting a tool in said opening.
2. A restrictor according to claim 1 in which said malleable material is brass.
3. A flow restrictor for a conduit having an internal passage extending therethrough, comprising an open-ended tube of malleable metal having a passage extending therethrough, the tube being of lesser outside diameter than the inside diameter of the conduit, a collar fixed around said tube and being of an outside diameter sufficient to span the conduit passage, means for securing the collar in the conduit with the tube extending longitudinally in the conduit, one end of the tube extending beyond the collar, said one end being pinched to provide an end opening which is smaller in area than the cross sectional area of said tube passage.
4. A flow restrictor for a conduit having an internal passage extending therethrough, comprising an originally cylindrical tube of circular cross section formed of malleable metal, the tube having an open ended passage extending axially therethrough and being of lesser outside diameter than the diameter of said conduit passage; a collar having a cylindrical outside wall, opposed annular end faces and a bore extending axially therethrough, screw threads formed in said cylindrical wall for threadably securing the restrictor in the conduit; the tube being of greater axial length than the collar, the tube being fitted in said bore to a position where the ends of the tube extend beyond respective end faces of the collar, one end of the tube being flared outwardly beyond the walls defining said bore thereby preventing the tube from sliding in one direction out from the bore, the other end of the tube being pinched in the walls thereof to form the tube open-

ing of said other end into an elongate opening of an area which is less than the cross sectional area of that portion of the tube passage positioned between the planes of said annular end faces, the tube having a transverse dimension in that portion thereof adjacent said other end which is greater than the diameter of said bore, thereby preventing the tube from sliding out from the bore in a direction opposite to said one direction.

5. A conduit having an internal passage extending therethrough defining an upstream opening at one end of the passage and a downstream opening at the opposite end of the passage, a flow restrictor secured in the passage, said restrictor comprising an open-ended tube of malleable material spaced from the walls defining the conduit passage, a collar fixed around the tube and spanning the space between the tube and the walls defining the conduit passage, said tube having one end thereof directed toward the downstream opening in the conduit and extending beyond the collar, said tube having opposite portions of the walls thereof adjacent said one end of the tube bent toward each other to define a tube opening which is smaller in area than the inside cross sectional area of any other part of the tube.

6. A lawn sprinkler system comprising a conduit having an internal passage therein, one end of the conduit being a downstream end and the other end being an upstream end adapted to be connected to a water supply line, said passage being closed in the downstream end thereof, a plurality of open-ended tubular risers extending upwardly and being connected at spaced apart points to the conduit for flow of water from the conduit passage up through the risers, a plurality of sprinkler heads connected respectively to the upper ends of the risers, each

riser having a flow restrictor releasably secured therein, each restrictor comprising an open-ended tube extending longitudinally in its respective riser whereby one end of the tube is a lower end and the other tube end is an upper end, said tube being spaced from the inside walls of its respective riser, a collar fixed around the tube and spanning the space between the tube and the said inside walls of its respective riser, the lower end of the tube defining a tube opening which is smaller in area than the internal cross sectional area of any other portion of the tube, and the lower end tube openings of the plurality of restrictors in the system being successively of greater area from the upstream end of the conduit to the downstream end thereof.

15 7. A lawn sprinkler system according to claim 6 in which said tubes extend downwardly from their respective collars and substantially to the cylindrical surface defining the conduit passage.
